ABRADING UNIT

Edwin H. White, Baltimore, Md.

Application November 30, 1948, Serial No. 62,670

1 Claim. (Cl. 51-190)

1

The present invention relates to an abrading unit for use in a specially designed spindle which is adapted to rotate the abrading unit within a cylindrical bore for treating the inner surface thereof.

The unit is principally constructed of a flexible abrasive material, such as sandpaper, or emery cloth, of a predetermined size, an elastic supporting member for supporting the abrasive material, and a holding clamp for securing together one of the two lateral edges of the abrading material and the supporting member.

The primary object of the invention is to provide an improved supporting member for an abrasive cloth, or material, operating within a cylindrical bore.

Another object of the invention is to provide an abrading unit which will be more uniform in its action, simpler in construction, and economical to manufacture.

While several objects, uses, and advantages of the invention have been specifically pointed out, other uses and advantages may also become apparent as the invention is more fully disclosed in the detailed description and accompanying drawings in which:

Figure 1 is a vertical sectional view of a special spindle for supporting the abrasive units in operating position.

Figure 2 is an enlarged view in elevation of one form of the abrasive unit.

Figure 3 is an enlarged end view of a modified form of unit.

Figure 4 is an enlarged view in elevation of still another modified form of the abrasive unit.

Figure 5 is a sectional view taken along the line 5-5 of Figure 4.

Figures 6 and 7 are sectional views of still a further form of above unit.

Figure 8 is a view taken along the line 8-8 of Figure 2.

Referring to the drawings and particularly to Figures 4 and 5, which is the preferred form of the invention, there is shown an abrasive unit comprising an abrasive sheet 10, a supporting member 12 and a holding clamp member 14. The abrasive material is composed of a pliable cloth-like material, or paper, carrying an abrasive material on its face. The supporting element is constructed of an elastic plastic material of substantially the same consistency throughout its area and is reduced in thickness in the direction of one of its lateral edges. The support provides an elastic backing for the abrasive materials and by its tapered surface its elasticity is

increased as the free edge 12' of the support is approached.

The holding and clamping member 14 is formed of a rigid material such as metal, a hard plastic, or the like.

To form the abrading unit, an abrasive material 10 is cut to a predetermined size, as best shown in Figure 4, in which there is provided several slots 16, 16' and 16''. Adjacent the member 10 there is placed the supporting member 12 which is preferably substantially narrower in width than the member 10. The members 10 and 12 are clamped together along one of their lateral edges by the holding and clamping member 14 which is upset at several points 17 and 17' for increasing the holding action of the holding clamp.

As mentioned before, this preferred form of supporting member 12 is tapered toward one of its lateral edges. In assembling the unit the thick portion 12' of the support is the portion to be clamped by the holding member 14, and the thinner portion 12'' extends outwardly in the direction of the free edge 10' of the abrasive member.

The clamped edges of the abrasive members and the supporting members are defined along the general line 13 which is substantially the same as the inner surface of the closed end of the U-shaped clamping member 14. In Figure 3 there is illustrated a modified form of support which is quite similar to that shown in Figures 4 and 5. In this form the support 20 is reduced in thickness by a series of steps 20' and 20'' which have substantially the same effect in increasing the elasticity of the support as its free edge is approached.

Figures 6 and 7 show still another form of support in which the supporting member 22 is originally formed with both lateral edges 22' and 22'' tapered, and when assembled the edge 22' is folded over upon the edge 22'' and clamped together with the abrasive member 10 by the member 14, as shown in Figure 7.

A still further modification is shown in Figures 2 and 8. In this particular supporting member, the support 24 is of uniform thickness and the flexibility of the member is determined by the number and location of the apertures 26. By placing these apertures close together and adjacent the free edge 24' the member is made more elastic in this area. These apertures may be of any convenient number, or size, which will sufficiently increase the normal elasticity of the support as the free end 24' is approached.

These supporting members, as previously mentioned, are constructed of any suitable plastic material. Those formed with a constant, or stepped lateral taper, are formed by extruding a plastic, of uniform consistency, through a die in an elongated strip of predetermined dimensions and later cutting the supports to the required length from the strip.

To form the modified supporting member 24, shown in Figure 2, a sheet of plastic material of uniform thickness is formed of the proper width and the desired perforations which are either punched, or impressed in the material at the time it is formed.

These abrading units are adapted to be inserted into a special spindle as shown in Figure 1. The spindle comprises a central shaft 30 particularly adapted to be receivable into a standard chuck of a portable electrical hand drill. There is an upper cap 32 and a lower cap 34 for holding the ends 14' and 14'' of the holding member 14 and a central body portion 36 having slots 38 for receiving the end portions 14' and 14'' of the member 14 and to hold them in a substantially radial position. The abrading units are held within the spindle by the nut 40 operating against the bottom cap 34.

In operation, the shaft 30 is locked in a rotatable chuck and inserted into a cylinder (not shown) the outer ends of the abrasive member 10 will contact the cylinder walls upon rotation of the spindle and perform an abrading action thereon. The elastic supports are adapted to keep the abrasive members in constant contact with the cylinder wall as they are rotated within the bore.

While the present disclosure describes and illustrates several specific species of the improved abrasive unit, it is not intended to be a limitation,

as the scope of the invention will be best defined in the appending claim in which I claim:

An abrading unit for portable cylinder treating tools having a rotatable holding frame for said unit, said unit comprising a single U-shaped clamping member having its ends extending outwardly beyond the unit to engage the tool holding frame, a thin flexible abrasive sheet, a single tapered elastic supporting sheet of substantially the same size as the thin sheet for supporting the same, the U-shaped clamp adapted to clamp the thicker edge of the tapered member and the single edge of the thin abrasive member together throughout their entire length to form a single integral unit whereby the thin abrasive sheet and the tapered sheet are held in close contact with each other by the said clamp which in turn is holdable within the tool holding frame.
